UNITED STATES PATENT OFFICE.

HERBERT R. BLISS, OF NIAGARA FALLS, NEW YORK.

SHIPPING CASE.

Application filed August 7, 1924. Serial No. 730,768.

This invention relates to a paper or straw board box and particularly to the construction thereof. This application is a continuation in part of my pending application 5 Serial No. 605,301, filed December 6, 1922.

The chief object of the invention is to construct a paper or straw board box for canned goods and the like in an improved manner, such that the portions subjected 10 to the greatest strain and wear in its use will be reenforced and that the box may be constructed of but a few parts with a minimum of waste material.

The chief feature of the invention consists in constructing a paper or straw board box of but three parts in such a manner that the several parts cooperate with each other so as to provide a strengthened construction as well as an economical construction.

The full nature of this invention will be understood from the accompanying drawings and the following description and claim.

In the drawings:

25 Fig. 1 is a perspective view of a box embodying the invention.

Fig. 2 is a plan view of the main box blank.

Fig. 3 is a cross sectional view of the box.

30 Fig. 4 is a sectional view of the end of the box and is taken on the line 4-4 of Fig. 1, and in the direction of the arrows.

Fig. 5 is a perspective view of the sealed case, sealed in the way that I prefer.

35 In the drawings 10 indicates the bottom and 11 the side portions of the box, while 12 indicates the top flap portions. As shown clearly in Fig. 2, the top flaps, sides and the bottom are formed from an integral sheet of 40 paper or straw board and each end of the sides is provided with an end retaining strip 13, while each end of the bottom is provided with an end retaining strip 14. Each of the aforesaid sub-divisions are integral with each

45 other and separated by creases, these creases all being formed on the same side of the sheet. This permits the simplification of the manufacturing machinery such that the main box blank may be cut from a suitable 50 sheet and creased in the same operation.

There are also provided two end members, the end forming portion being indicated by the numeral 15 and the top flap portion being indicated by the numeral 16. As shown clearly in Figs. 1, 2 and 3, the main box blank is folded into trough-like shape and the end strips are turned at right angles to the sides and bottom and therefore inwardly towards each other. The end blanks are positioned within the trough-like blank in 55 abuttable relation to the end strips 13 and 14 to which they are secured by the staples 17, or by any other suitable means. In this fashion it will be noted that the corners of the box include an integral edge in each 60 instance and that the ends of the box are protected by the retaining strip, thereby greatly increasing the strength of the box. In particular, when the box is used with canned goods the end piece 15 spaces the 65 ends of the cans from the crease between the strip 14 and bottom 10 so that the can ends cannot reach the crease.

I prefer to seal this shipping case by wire stitching as shown in Fig. 5. The method 75 by which the wire stitching may be done is described and claimed in my Patent No. 1,452,588 dated April 24, 1923, but it is obvious that the case might be sealed in other ways.

80 What I claim is:

A paper or straw board box comprising a main body blank providing a box bottom, two sides, two top flaps, said top flaps being arranged to fold towards each other over the top of the box so their edges will meet each other, and end securing strips folded over each end of each side and each end of the bottom, a pair of end blanks each providing a top flap so positioned as to fold over the 85 top of the box so as to lie adjacent the under surface of the top flaps, and means for rigidly securing said end blanks to said end securing strips, substantially as described.

90 In testimony whereof I have affixed my 95 signature.

HERBERT R. BLISS.
